JEREMONT J. MACBETH, OF DAYTON, OHIO.

GASOLENE-DISPENSING PUMP.

1,301,861.

Specification of Letters Patent. Patented Apr. 29, 1919.

Application filed August 1, 1918. Serial No. 247,827.

To all whom it may concern:

Be it known that I, JEREMONT J. MACBETH, a citizen of the United States, residing at Dayton, in the county of Montgomery and 5 State of Ohio, have invented certain new and useful Improvements in Gasolene-Dispensing Pumps, of which the following is a specification.

This invention relates to certain improvements in gasoline or kerosene oil dispensing pumps. The object of the invention is to provide a pump of this character with a capacity for discharging given quantities of gasoline or kerosene oil to purchasers with 10 accuracy so that it may be known that the correct quantity or quantities purchased are being delivered, said pump having the structural characteristics hereinafter described and claimed. In the accompanying drawings Figure 1 is a side elevation of a gasoline or kerosene oil pump constructed in accordance with my invention, and Fig. 2 is a front elevation thereof.

In a detail description of the said invention similar reference characters indicate corresponding parts in the drawings. The gasoline or kerosene oil is pumped into a tank 1 which is located at the top of the frame structure and is discharged from said 15 tank through a spout 2 which communicates with the lower portion of the chamber of said tank through a valve 3. The chamber member or tank 1 is supported upon an open frame 4 which extends upright from the 20 pump base 5 which rests upon the floor. The tank 1 has a glass indicator tube 6 on a side thereof which communicates with the chamber of the tank and records the level of the gasoline in said chamber. Coöperating 25 with the indicator tube 6 is a calibrated scale 7 arranged adjacent thereto on the tank 1 to indicate the quantity of gasoline or kerosene discharged by the pump through the spout 2. Located in the lower portion 30 of the pump frame is a gasolene pump consisting of cylinder 8 and a piston 9 which is driven from a piston rod 10 having fixed to the upper end thereof a rack 11. The cylinder 8 receives through suction, gasoline 35 alternately above and below the piston 9 from the pipe 27 which pipe connects with the source of supply of gasoline. The said gasoline is forced out by said piston 9 through a discharge pipe 12 which extends 40 up to the top of the tank 1 and discharges 45 therein. The pipe 27 communicates with the upper and lower ends of the cylinder 8 through valves 27' and 28' which are operated automatically to open at one end of the cylinder and close at the other end through 50 the suction and pressure created through the reversing of the piston 9. The gasoline discharge pipe 12 has arranged at the top and bottom of the cylinder 8 communications controlled by valves 13 and 14 which are 55 similarly operated and which control the passages between the cylinder 8 and the pipe 12. 15 designates a twin air cylinder mounted beside the cylinder 8 and having a piston 16 which drives a rod 17 connected thereto 60 and a rack 18 connected to said rod. 19 designates a gear wheel which is engaged on opposite sides by the racks 11 and 18 so that when said gear wheel 19 is driven by the air 65 actuated piston 16 to the gasoline piston 9 is 70 likewise driven to pump the gasoline up through the pipe 12. The shaft 20 of the gear wheel 19 is journaled in bearing parts 75 21 that extend across the pump frame and the said shaft has an end 22 shaped to receive a crank handle by which the pump 80 may be operated manually should the air supply fail. 23 designates an air supply pipe for the piston 16 extending from a source of compressed air. This pipe 23 extends 85 from the source of compressed air and communicates with the upper and lower ends of the air cylinder 15 through valves 24 and 25 to admit air under compression above and 90 below said piston 16 to drive the same and 95 therewith the rack 18, gear 19 and the gasoline piston 9. This air pipe 23 also communicates with the top of the tank 1 and air is admitted to the interior of the tank 100 through a valve 26 to accelerate the discharge of gasoline through the spout 2 when the valve 3 is open. The pipe 27 connects with the bottom of the tank 1 through an apertured member 28 to which the outlet spout 2 is also connected. This pipe 27 also 105 acts as a drain for any excess gasoline that may be discharged into the tank 1. When thus used the valve 29 is opened. The operation of the pump is as follows:

It being desired to discharge a given quantity of gasoline from the pump, the valves 24 and 25 of air pipe 23 are opened alternately to admit air to drive the piston 16. The gear wheel 19 is thus operated to drive the gasoline piston 9 until the requisite 110

amount of gasoline, determined upon by the tube 6, enters the tank 1. The discharge spout 2 is then opened by turning the valve 3 to discharge the quantity of gasoline so indicated from the pump and the air valve 26 is opened to force the oil more rapidly out through the spout 2.

Having described my invention I claim:

1. In a gasoline dispensing pump, a frame, a gasoline tank mounted thereon having a quantity-measuring indicator, a gasoline pump, a gasoline supply pipe communicating with said pump, a gasoline discharge pipe communicating with said pump and said tank, an air-driven motor geared to the gasoline pump, and an air supply pipe supplying air to said motor and to the upper portion of the gasoline tank, substantially as specified.

2. In a gasoline dispensing pump, the 20 combination with a supporting base and frame, of a gasoline tank supported in said frame, twin cylinders mounted on said base having pistons therein and constituting a gasoline pump and a motor respectively for 25 said gasoline pump, a gasoline supply pipe communicating with the lower portion of said tank and with the gasoline pump, a gasoline discharge pipe communicating with the upper portion of said tank and said gasoline pump, and an air supply pipe communicating with the upper portion of said tank and with the said motor and providing means for operating said pump and supplying air pressure to the upper portion of the 30 tank, substantially as specified.

In testimony whereof I affix my signature.
JEREMONT J. MACBETH.
